UNITED STATES PATENT OFFICE.

ELI H. JANNEY, OF FAIRFAX COUNTY, VIRGINIA.

CAR-COUPING.

974,153.

Specification of Letters Patent.

Patented Nov. 1, 1910.

Application filed March 21, 1907. Serial No. 363,635.

To all whom it may concern:

Be it known that I, ELI H. JANNEY, a citizen of the United States, residing in Fairfax county, State of Virginia, have invented new and useful Improvements in Car-Couplings, of which the following is a specification.

My invention relates to car couplings of the "Janney" type, and has for its object to provide certain improvements over the construction disclosed in an application filed by me June 18, 1906, Serial No. 322,331, as will be hereinafter more definitely described and claimed.

15 In the accompanying drawings: Figure 1 is a perspective view of my improved coupling, showing an improved means for operating the locking pin. Fig. 2 is a central vertical longitudinal sectional view, the locking pin being shown partly in elevation and partly broken away. Fig. 3 is a vertical transverse sectional view taken just in front of the locking pin, showing said pin in full lines in its lowermost or locking position, and in dotted lines in the lock-set position. Fig. 4 is a view similar to Fig. 3, the coupling hook being swung open and the locking pin being shown raised to the highest position it will assume when lifted 20 by said coupling hook. Fig. 5 is a central horizontal sectional view, the coupling hook being shown in plan, and the draw head being partly broken away to show underlying parts. Fig. 6 is a view similar to Fig. 2, 30 but looking in the opposite direction, the locking pin and coupling hook being removed. Fig. 7 is an enlarged detail perspective view of the locking pin. Fig. 8 is a similar view of the coupling hook.

40 Similar numerals of reference denote corresponding parts in the several views.

In the said drawings the reference numeral 1 denotes the draw-bar of the coupling, carrying the draw-head 2, in which 45 is pivoted, by means of the pin 3, the usual coupling hook 4. Passing vertically through the upper and lower apertures 5 and 6 in the draw-head 2 is the locking pin 7, the same being recessed on its front side 50 at 8 and having the upper face of said recess formed with a relatively long inclined or cam surface 9 and with a relatively short inclined, or cam surface 10, inclining in the opposite direction from that of incline 9, the 55 meeting edge 11 of said inclines being on a

slight incline upward and forward, as best seen in Figs. 3 and 4. The lower face of said recess 8 is formed with a cam surface 12 inclining in a direction the reverse of cam surface 9 and having its upper end projecting beyond the side face of the pin. As seen in Fig. 2, the upper portion of said cam surface 12 is inclined downwardly from front to rear at 13. Below the recess 8 in the pin 7 is another recess 14, having its upper edge inclined upwardly and inwardly at 15 to engage a cotter pin 16 removably located in the draw-head, said cotter pin performing the function of supporting the locking pin in the lock-set position. The tail of the coupling hook 4 is reversely inclined on its upper and lower surfaces at 17 and 18 to correspond with the inclines 9 and 12 on the locking pin, the lower incline 18 being also inclined at 19 to correspond with the incline 13 on the pin 7, as shown in dotted lines in Fig. 2 said incline 19 lying parallel in said figure with the incline of the meeting edge 11 of inclines 9 and 10 on the locking pin 7.

Referring to Fig. 2, it will be seen that the rear wall of the apertures 5 and 6 in the draw-head is slightly concaved to correspond with a similar convexity 20 on the rear face of the locking pin 7, the object of the same being to cause said pin, when lifted by the movement of the coupling hook to the closed position, to hug said concaved surface, whereby, when released by said coupling hook, it will drop free from the lock-set pin 16 to its locking position. The cam surface or incline 12 of locking pin 7 is projected at its lower end to the right, said projection performing the double function of an anticerping device and a means for throwing the lower end of the locking pin to the left beneath the tail of the coupling hook. Further, said locking pin is provided with the incline 22, which, when the locking pin is in its lowermost position, engages a similar incline 23 formed in the lower aperture 6 of the draw-head, to impart an initial lift to the locking pin when contacted with by the coupling hook tail in its movement to the closed position.

All of the above parts being constructed to operate as described in my application hereinbefore referred to, further detailed description of the same is deemed unnecessary.

In my improved construction the projection to the right of cam surface or incline 12 aids in performing still another important function, as follows: In this class of couplings the dropping of the locking pin to its lowermost position when the coupling hook is opened has been prevented heretofore by extending the tail of the coupling hook so that it will act as a support for the locking pin at all times except when said coupling hook is in its closed position. Applicant accomplishes this result without employing the extension on the coupling hook tail by providing a recess 24 in the side wall 15 of the draw-head opposite to the coupling hook tail when the latter is in its closed position, said recess being inclined forwardly at its lower end at 25 and merging into another incline 26 at a right angle 20 thereto, said latter incline overlying the cotter pin 16 that constitutes part of the lock-set mechanism, as best seen in Figs. 3, 4, 5 and 6. Now, when the locking pin 7 is in the lock-set position, as shown in dotted lines in Fig. 3, and the coupling hook begins 25 to move toward the open position, the tail of said coupling hook, by its contact with the incline 10 on said locking pin, will raise said locking pin to disengage it from the lock-set, and will at the same time force the lower end of said locking pin to the right, so that, when the edge 11 on said locking pin comes in contact with the coupling hook tail, said locking pin will have assumed the 30 position shown in Fig. 4, with the projection of its cam surface or incline 12 lying in the recess 24 in the draw-head, it being apparent that the movement of the locking pin above described is permitted initially 35 by the sliding contact between the inclines 26 and 27 on the draw-head and locking pin, respectively. Now, as said locking pin is released by the further movement of the coupling hook tail toward the open position, it will drop, but, being guided by the engagement of the projection of incline 12 with recess 24, the under inclined surface 27 of the former will ride forward on the incline 25 and from thence onto the incline 50 26, which will cause the aperture 14 in said locking pin to again engage the cotter pin 16, thereby supporting said locking pin in the lock-set position. It is desirable that this seating of the locking pin on the lock-set shall also occur when the coupling hook is thrown open by lifting the locking pin until the incline 12 thereon contacts with the incline 18 on the coupling hook tail, and this result is insured by providing an incline 55 60 65 28 on the side of the locking pin 7, and a corresponding incline 29 in the draw-head 2, said inclines contacting as the locking pin approaches its highest limit of movement, which forces the lower end of said locking pin to the right, so that the projection of

incline 12 thereon will engage in the recess 24 under this movement, and, when the locking pin is released to drop, the inclines 25 and 26 will guide said locking pin to cause it to fall onto the lock-set.

It is desired that when the locking pin 7 is lifted to throw open the coupling hook, the lower end of said locking pin move to the right to follow the coupling hook tail in its opening movement. This function is 75 performed by my inclines 28 and 29, and by reason of their location intermediate the length of the locking pin, this movement of the lower end of the locking pin is accomplished by means of smaller inclines than is 80 necessary when said motion is imparted from the lower end of the locking pin. It will thus be seen that said inclines perform the double function of causing the lower end of said locking pin to follow the coupling hook tail in its opening movement, and of causing said locking pin when released to drop onto the lock-set. By these means I provide for the seating of the locking pin on the lock-set whenever the coupling hook is opened, the result being that on the return of the latter to the closed position it is necessary to lift the locking pin only a slight distance, thereby practically accomplishing the result heretofore obtained by extending the tail of the coupling hook to form a locking pin support during the entire open movement of said coupling hook.

I do not wish to confine myself to the use 100 of both the inclines 26 and 27, as it will be evident that either one of the same may be dispensed with and the desired result still obtained, though possibly not in so satisfactory a manner. The incline 12 on the 105 locking pin is projected to the left to more surely engage with the incline 18 on the coupling hook tail when it is desired to throw open the coupling hook by means of said locking pin, this operation being aided 110 by the contact of extension 21 of incline 12 on the locking pin with the draw-head. Now, to still further facilitate this result, I have projected the incline 18 on the coupling hook tail to the right beyond the engaging face of the coupling hook tail with the locking pin, as shown at 30, the result being that the area of initial contact between the inclines 12 and 18 is correspondingly increased, and the initial opening 115 120 movement of the coupling hook thereby facilitated.

In Figs. 1 and 2 I have illustrated an improved lifting means for the locking pin 7, the same consisting of the usual crank 125 rod 31 pivoted in bearings 32 mounted on the car sill (shown in dotted lines, Fig. 2), and connected with the locking pin by means of a single elongated link 33. The looped portion 34 of the crank rod 31 is of com- 130

paratively broad area to permit a free lateral movement of the link 33, required because of the lateral movement of the draw-bar in rounding curves, said construction 5 permitting the link 33 to remain substantially vertical in any position of the draw-head, whereby the locking pin may be readily operated on the sharpest curves. Said link 33 is pivoted to the locking pin 7 between two ears 35 to maintain said link 10 substantially vertical. By employing this single connecting link 33 in place of the usual chain connecting the crank rod with the locking pin, I am enabled to dispense 15 with clevises on top of the locking pin and on the crank rod, thereby materially simplifying the construction of this part. A further important advantage obtained by employing the single elongated link 33 is 20 that by means of the same the locking pin 7 may at any time be thrown off the lock-set when, for instance, it has been so set by mistake. Thus, with the locking pin in the lock-set position, as shown in dotted lines 25 in Fig. 2, the link 33 will assume the position shown in dotted lines therein, with the cranked portion 34 of crank rod 31 positioned therein below the longitudinal center of said link. Now, as the crank portion 30 34 of crank rod 31 is held against further downward movement by the contact of said cranked portion with the car sill, shown in dotted lines in Fig. 2, said cranked portion will act as a fulcrum for said link, and upon 35 pressure being applied, or a blow struck, to the upper end of link 33 in a rearward direction, said link will act to lift and force the upper end of the locking pin 7 forward, thereby forcing its lower end rearward and 40 out of its engagement with the cotter pin 16, and thus releasing said locking pin from the lock-set position.

As shown in Fig. 2, there is located in the rear of upper aperture 5 in the draw-head a 45 stop pin 36 engaging in an elongated vertical slot 37 in the rear face of the locking pin 7, the same limiting the vertical movement of said locking pin when the latter is operatively positioned in the draw-head, 50 and also preventing the withdrawal of the locking pin. To withdraw said locking pin 7 I provide a through aperture 38 in the locking pin 7 through which said stop pin 36 may be reached to remove the same.

55 Having thus described my invention, what I claim as new and desire to secure by Letters Patent is:

1. In a car coupling, the combination with the draw-head, a coupling hook pivoted 60 therein, a vertically movable locking pin for said coupling hook, and a lock-set for said locking pin, of coöperating means in said draw-head and on said locking pin for causing said locking 65 pin to engage and be supported by said lock-

set under any opening movement of said coupling hook.

2. In a car coupling, the combination with the draw-head, a coupling hook pivoted therein, a vertically movable locking pin for said coupling hook, and a lock-set for said locking pin, of coöperating means in the side of said draw-head and on said locking pin for causing said locking pin to engage and be supported by said lock-set under any opening movement of said coupling hook. 75

3. In a car coupling, the combination with the draw-head, a coupling hook pivoted therein, a vertically movable locking pin for said coupling hook, and a lock-set in said draw-head for said locking pin, of an incline in the side of said draw-head, and a projection on said locking pin, coöperating, when said locking pin is lifted during 80 any opening movement of the coupling hook, to cause said locking pin, when released, to engage and be supported by said lock-set. 85

4. In a car coupling, the combination with the draw-head, a coupling hook pivoted therein, a vertically movable locking pin for said coupling hook, and a lock-set in said draw-head for said locking pin, of a double incline lying in a recess in said draw-head, and a projection on said locking pin, the 90 whole coöperating, when said locking pin is lifted during any opening movement of said coupling hook, to cause said locking pin, when released, to engage and be supported by said lock-set. 95

5. In a car coupling, the combination with the draw-head, a coupling hook pivoted therein, a vertically movable locking pin for said coupling hook adapted when raised to its upward limit of movement to force said 100 coupling hook to the open position, a lock-set for said locking pin, and means for causing said locking pin to move toward and engage said lock-set after forcing said coupling hook open. 110

6. In a car coupling, the combination with the draw-head, a coupling hook pivoted therein, a vertically movable locking pin for said coupling hook, a lock-set in said draw-head for said locking pin, and coöperating means on said draw-head and locking pin which, when engaged, will cause said locking pin, when released, to move toward and engage with and be supported by said lock-set, of means for causing said coöperating means to engage when said locking pin is lifted to its upward limit of movement. 115

7. In a car coupling, the combination with the draw-head, a coupling hook pivoted therein, a vertically movable locking pin for said coupling hook, a lock-set in said draw-head for said locking pin, and coöperating means on said draw-head and locking pin which, when engaged, will cause said locking pin, when released, to engage with and 120 lift to its upward limit of movement. 125

130

be supported by said lock-set, of coöperating inclines on said draw-head and locking pin for causing said coöperating means to engage when said locking pin is lifted to its upward limit of movement.

8. In a car coupling, the combination with the draw-head, a coupling hook pivoted therein, and a vertically movable locking pin for said coupling hook having a vertical slot therein and a through aperture registering with said slot, of a removable retaining pin in the draw-head engaging said slot in the locking pin to limit the vertical move-

ment of the latter, said through aperture in said locking pin adapted to register with said retaining pin when said locking pin is raised, in which position said retaining pin may be forced out of operative position to permit the withdrawal of said locking pin.

In testimony whereof I have hereunto set my hand in the presence of two subscribing witnesses.

ELI H. JANNEY.
